DESIGN FOR A PAPER WRAPPER FOR A CANDY BOX

Samuel H. Born, Bethlehem, Pa.

Application June 23, 1947, Serial No. 139,875

Term of patent 3½ years

(Cl. D59—2)

To all whom it may concern:

Be it known that I, Samuel H. Born, a citizen of the United States, residing at Bethlehem, in the county of Northampton and State of Pennsylvania, have invented a new, original, and ornamental Design for a Paper Wrapper for a Candy Box, of which the following is a specification, reference being had to the accompanying drawing, forming a part thereof.

In the drawing the figure is plan view of a paper wrapper for a candy box, showing my new design.

The central heart-shaped figure and the small circular elements immediately surrounding same are lined to indicate color contrast.

I claim:

The ornamental design for a paper wrapper for a candy box, as shown and described.

SAMUEL H. BORN.
